SPECTACLE FRAME OR THE LIKE

Walter C. Carmichael, Lexington, Mass., assignor to American Optical Company, Southbridge, Mass., a voluntary association of Massachusetts

Filed July 19, 1960, Ser. No. 61,427

Term of patent 14 years

(Cl. D57—1)

FIG. 1 is a front elevation view of a spectacle frame embodying my new design; and

FIG. 2 is a top plan view thereof.

The temples are shown broken away in FIG. 2 for convenience of illustration.

The rear of the frame not shown is substantially plain.

The dominant features of my new design are shown in full lines in the drawing.

I claim:

The ornamental design for a spectacle frame or the like, substantially as shown and described.
